US0D1027007S

(12) **United States Design Patent** (10) **Patent No.:** **US D1,027,007 S**
(45) **Date of Patent:** **** May 14, 2024**

(54) **HANDHELD TRIPOD CLIP**

(71) Applicant: **SHENZHEN YUANSU CHUANGDA TECHNOLOGY CO., LTD**, Shenzhen (CN)

(72) Inventor: **Xibin Xu**, Shenzhen (CN)

(73) Assignee: **SHENZHEN YUANSU CHUANGDA TECHNOLOGY CO., LTD**, Shenzhen (CN)

(**) Term: **15 Years**

(21) Appl. No.: **29/833,761**

(22) Filed: **Apr. 6, 2022**

(30) **Foreign Application Priority Data**

Jan. 6, 2022 (CN) 202230006393.2

(51) **LOC (14) Cl.** **16-05**

(57) **CLAIM**

The ornamental design for a handheld tripod clip, as shown and described.

DESCRIPTION

FIG. 1 is a perspective view of a handheld tripod clip showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the handheld tripod clip where the handheld tripod clip is in a configuration of use. The broken lines immediately adjacent to the shaded areas depict the bounds of the claimed design, while all other broken lines in FIG. 9 are directed to environment. The broken lines form no part of the claimed design.

1 Claim, 9 Drawing Sheets
